United States Patent Office

Des. 187,645
Patented Apr. 12, 1960

187,645

DENTAL-UNIT

Taichi Yamanaka, Tokyo, Japan

Application January 29, 1958, Serial No. 49,437

Term of patent 7 years

(Cl. D24—1)

Des. 187,645

PAGE 2

~~FIG~~ 3

~~FIG~~ 4

Fig. 1 is a right side elevational view of a dental-unit embodying my new design;

Fig. 2 is a front elevational view thereof;

Fig. 3 is a left side elevational view thereof;

Fig. 4 is a rear elevational view thereof; and

Fig. 5 is a front perspective view thereof.

I claim:

The ornamental design for a dental-unit, substantially as shown.
